Primary Examiner — George D. Kirschbaum*Assistant Examiner* — Kendra Leslie Hamilton(74) Attorney, Agent, or Firm — Zollinger & Burleson Ltd.(57) CLAIM

The ornamental design for a holder for a holder for pet chew toy, as shown and described.

DESCRIPTION

FIG. 1 is a top front right perspective view of a holder for pet chew toy showing our new design;

FIG. 2 is a top plan view thereof;

FIG. 3 is a front elevation view thereof;

FIG. 4 is a right side elevation view thereof;

FIG. 5 is a left side elevation view thereof;

FIG. 6 is a bottom plan view thereof; and,

FIG. 7 is a rear elevation view thereof.

The broken lines in the drawings depict portions of the holder for pet chew toy that form no part of the claimed design.
